(No Model.)

M. W. BRUCE.

HOSE SUPPORTER.

No. 407,810.

Patented July 30, 1889.

Fig. 3.

UNITED STATES PATENT OFFICE.

MINER W. BRUCE, OF KNOX CENTER, NEBRASKA.

HOSE-SUPPORTER.

SPECIFICATION forming part of Letters Patent No. 407,810, dated July 30, 1889.

Application filed November 8, 1888. Serial No. 290,392. (No model.)

To all whom it may concern:

Be it known that I, MINER W. BRUCE, of Knox Center, in the county of Knox and State of Nebraska, have invented a new and 5 Improved Hose-Supporter, of which the following is a full, clear, and exact description.

The main object of the invention is to furnish a hose-supporter in which any slack in the elastic band of the supporter caused by 10 the stretching of the same will be automatically taken up by the clasp-carrying cord.

The invention consists in the novel construction and combination of parts hereinafter described and claimed.

15 Reference is to be had to the accompanying drawings, forming a part of this specification, in which similar letters of reference indicate corresponding parts in all the figures.

Figure 1 is a side illustration of my improved hose-supporter in use. Fig. 2 is a 20 perspective view of the supporter, and Fig. 3 is a perspective view of a modification to be hereinafter referred to.

The divided band A of the supporter, which 25 encircles or rather partly encircles the leg of the wearer, is preferably made of elastic material, as usual, and is provided at each end with a hook B. The hooks B I prefer to make of the form of the ordinary lacing- 30 hooks, in which the overhanging head is united to the fastening-eyelet by a shank or neck b at one side of the head. The ends of the band A are turned inward and secured to cover the metallic rivet portion of the hooks 35 B, thus preventing any discoloration of the garments on account of rusting. An endless cord C is passed over the hooks B, to lie beneath the overhanging heads thereof and move freely thereunder, and is also passed 40 under another like hook B', secured to the clasp D, which clasps the upper end of the

hose. The clasp D, with the exception of its hook B', may be of any approved construction. The cord C, lying loosely under the lacing-hooks, has a tendency to draw the ends 45 of the band A toward each other, and thus, as the band stretches from continued use, the slack is taken up by the cord, and the band is thus at all times held snugly to the leg of the wearer. The cord C is free to slide in 50 the hooks B, and if at any time the cord should become worn in certain places it can be slid around so as to expose the strong portions to the hooks.

Instead of fastening the hook B directly to 55 the clasp D, it may be fastened to a leather loop D', carried by the clasp, as illustrated in Fig. 3.

Having thus described my invention, what I claim as new, and desire to secure by Let- 60 ters Patent, is—

1. The herein-described hose-supporter, consisting of a divided band A, having the hooks B B rigidly attached to its ends, a clasp D, also provided with a hook B' at its upper 65 end, and an endless cord C, passing around the hooks B B' and adapted to slide freely within the same, substantially as and for the purpose described.

2. The herein-described hose-supporter, 70 consisting of an elastic divided band A, having the hooks B B rigidly attached to its ends, a clasp D, carrying the loop D' in its upper end, said loop having a hook B' rigidly attached thereto, and the endless cord C, passing around all the hooks B B' and adapted 75 to slide freely within the same, substantially as and for the purpose described.

MINER W. BRUCE.
